CAR DOOR LOCK

Frank Ditchfield, Cleveland, Ohio, assignor to The Youngstown Steel Door Company, Cleveland, Ohio, a corporation of Ohio

Application May 13, 1948, Serial No. 26,781

5 Claims. (Cl. 292—286)

1

This invention relates to car door locks and particularly to locks for sliding doors of railway house cars.

It is an object of this invention to provide locks for sliding doors of railway house cars capable of compensating for normal inaccuracies of car construction and obviating back and forth lashing of the doors when locked.

A further object is to provide locks for sliding doors of railways house cars which shall embody tapered pins movable vertically when the doors are locked and which shall be so constructed as to positively limit upward movement of the pins.

A further object is to provide locks for sliding doors of railway house cars which shall embody tapered locking pins mounted so as to have both vertically reciprocating and swinging movements.

A further object is to provide locks for sliding doors of railway house cars which shall embody lock brackets carrying pivotally mounted members adapted to extend across vertical reciprocating tapered locking pins carried by the brackets, the lock bracket and members being so constructed and arranged so as to form door seals.

Other objects of the invention will become clear as the description thereof proceeds.

In the drawings forming part of this specification:

Fig. 1 is a fragmentary elevation of double sliding doors of railway house cars equipped with a lock embodying the instant invention.

Fig. 2 is a view similar to Fig. 1 showing the main door after it has been moved the maximum distance in opening direction by an opening and closing lever carried by the lock.

Fig. 3 is a horizontal section taken on line 3—3 of Fig. 1.

Fig. 4 is a vertical section taken on line 4—4 of Fig. 1.

Fig. 5 is a vertical section taken on line 5—5 of Fig. 2.

In the drawings the instant invention is illustrated embodied in a lock designed for application to the main and auxiliary doors 10 and 11 of a double door construction for railway house cars. These doors may be of any desired construction and as shown the main door is formed with a plurality of spaced horizontal corrugations 12 upon one of which a hasp fastener 13 is seated. The hasp fastener which is reinforced by means of a member 14 disposed within the corrugation is formed with a neck portion 15, the end 16 of which extends through aligned openings formed in a vertical corrugation 17 of the door and the hasp fastener reinforcement. The hasp fastener 13

2

swingably supports a hasp 18 by extending through an eye 19 formed in one end of the hasp. The hasp 18 is also formed with a pin engaging shoulder 20 and forwardly of said shoulder with an eye 21 for a purpose which will hereinafter appear.

The auxiliary door 11 is constructed similarly to the main door 10 so as to embody a plurality of spaced horizontal corrugations 22 and a vertical corrugation 23. On the auxiliary door is mounted the lock bracket 24 of the lock as by means of vertical rivets 25 and 26 and horizontal rivets 27 and 28.

The lock bracket 24 which is preferably in the form of a casting is provided with longitudinally spaced flanges 29 and 30. Below these flanges the lock bracket is formed with a ledge 31 which carries the angularly related flanges 32 and 33. Forwardly of the ledge 31 the lock bracket 24 is formed with a boss 34 upon which are pivotally mounted a member 35 and an opening and closing lever 36, these being retained upon the boss by means of a washer W and a rivet 37 extending through the washer, the boss, and the door. The bracket is also formed with a rib 38 for a purpose which will later appear.

A tapered pin 39 is supported between flanges 29 and 30 of the lock bracket in such a manner that it possesses both swinging and limited vertical movement. To this end, the upper portion of the pin is formed with an elongated slot 40 through which a securing rivet 41 carried by the flanges 29 and 30 extends. In this manner upward and downward vertical movement of the pin is restricted by the engagement respectively of the rivet 41 with the lower and upper ends of the slot 40. At the same time outward swinging movement of the pin about the rivet 41 is provided and, if desired, such movement may be limited by the engagement of a rib 42 formed on the upper edge of the pin with the rib 38 formed on the lock bracket. As will be apparent from the showing of Fig. 5 of the drawings the pin may be swung outwardly to such an extent as to permit outward swinging movement of the hasp 18 for disengagement from the lock bracket.

The lock is shown in its door locking position in Fig. 1 of the drawings. In this position the lever 36 is supported upon a ledge 43 carried by the lock bracket at its forward end and the pivotally mounted member 35 extends across the pin and its free end is supported upon the ledge 31 of the lock bracket. In this position of the lock, moreover, a boss 44 formed on the operating lever 36 extends through the eye 21 of the hasp. The

doors may be sealed by means of a seal, not shown, passing through the slot 45 formed in flange 33 and an alined slot 46 formed in flange 47 provided on the pivotally mounted member 35.

In the said position of the lock the shoulder 20 formed on the hasp abuts one edge of the tapered pin 39, thereby preventing separation of the doors. However, should the adjacent edges of the doors be spaced apart when the lock is in the position illustrated, relative movement of the doors toward each other may occur. Such movement will effect disengagement of the shoulder from the pin at which time the pin will drop by the action of gravity so as to restore such engagement. Movement of the hasp toward the left as viewed in Fig. 1 as the doors approach each other is made possible by means of the clearance provided between the boss 44 formed on the lever 36 and the eye 21 formed in the hasp. The rivet and slot connection between the bracket and the pin permits the pin to be lowered upon such movement of the doors.

It has been found that when cars equipped with locks embodying tapered pins are subjected to impact, there is a tendency for the pins to move upwardly. By means of the instant invention if the pin 39 should move upwardly, such movement is positively limited by the engagement of the rivet 41 with the lower end of the slot 40 formed in the pin. Moreover, as is shown by the dot and dash position of the pin when such engagement occurs, the lower portion of the pin still lies behind the member 35 so that the locking engagement between the pin and the hasp 18 is not disturbed.

Fig. 2 of the drawings shows the relative positions of the main and auxiliary doors after the main door has been moved in opening direction by means of the lever 36. To accomplish this, the seal is removed and the member 35 is released from the ledge 31 so that it hangs vertically from the boss 34. The pin 39 is then swung outwardly about the rivet 41, the extreme swinging movement being obtained when the rivet is engaged with the upper end of the slot 40 of the pin. The lever 36 is then moved upwardly in clockwise direction so that a thrust is exerted by the boss 44 formed on the lever against the hasp, thereby forcing the main door in opening direction. The hasp is then disengaged from the boss 44 and the opening movement of the main door may be completed. Thereafter the auxiliary door may be moved in opposite direction to its open position.

To close and lock the doors, the auxiliary door is closed and the main door moved at least to the position shown in Fig. 2 of the drawings. The hasp is then engaged with the boss 44 on the lever and at this time the pin 39 may be swung inwardly so as to rest upon the hasp. A pull upon the lever in counter-clockwise direction will move the main door toward the auxiliary door and as the shoulder 20 of the hasp moves forwardly beyond the pin, the latter will assume the vertical position shown in Figs. 1 and 4 of the drawings. Thereupon the member 35 may be seated upon the ledge 31 and a seal inserted through the alined slots 45 and 46.

It will be apparent that numerous changes and modifications in the details of the invention will be clear to those skilled in the art. It is intended, therefore, that all such changes and modifications be comprehended within this invention, which is to be limited only by the scope of the claims appended hereto.

I claim:

1. A lock for sliding car doors comprising a lock bracket, pivotally supported hasp, a tapered locking pin having a slot therein, a rivet secured to said bracket, said rivet extending through said slot and mounting said pin for swinging and limited vertical movements, a member pivotally mounted on said bracket and adapted to extend across said pin to prevent swinging movement thereof, and a ledge on said bracket adapted to support the free end of said member, said ledge and said free end of said member being formed with slots adapted to receive a door seal, said hasp having a shoulder adapted to have locking engagement with one edge of said pin, said pin in its uppermost vertical position extending behind said member.

2. A lock for sliding car doors comprising a lock bracket, a locking member, a slotted tapered pin adapted to have locking engagement with said member, means on said bracket extending through said slot and mounting said pin for swinging and limited vertical movements, and a releasable member mounted on said bracket and adapted to extend across said pin to prevent swinging movement thereof, said pin in its uppermost vertical position extending behind said releasable member.

3. A lock for sliding car doors comprising a lock bracket, a locking member, a tapered pin adapted to have locking engagement with said member, means on said pin and said bracket for mounting said pin for swinging and limited vertical movements, and a releasable member carried by said bracket and adapted to lie in front of said pin to prevent swinging movement thereof, said pin in its uppermost vertical position extending behind said releasable member.

4. A lock for sliding car doors comprising a lock bracket, a locking member, a slotted tapered pin adapted to have locking engagement with said member, means on said bracket extending through said slot and mounting said pin for vertical and swinging movements, said means being engageable with the lower edge of said slot to limit upward vertical movement of said pin, said means being disposed in the upper portion of said slot to permit outward swinging movement of said pin, and a releasable member mounted on said bracket and adapted to extend across said pin to prevent swinging movement thereof, said pin in its uppermost vertical position extending behind said releasable member.

5. A lock for sliding car doors comprising a lock bracket, a locking member, a slotted tapered pin adapted to have locking engagement with said member, means on said bracket extending through said slot and mounting said pin for vertical and swinging movements, said means being engageable with the lower edge of said slot to limit upward vertical movement of said pin, said means being disposed in the upper portion of said slot to permit outward swinging movement of said pin, a releasable member mounted on said bracket and adapted to extend across said pin to prevent swinging movement thereof, said pin in its uppermost vertical position extending behind said releasable member, and means on said lock bracket engaging said pin to limit outward swinging movement thereof.

FRANK DITCHFIELD.
